METHOD AND APPARATUS FOR
POSITIONING STRIP

Edwin T. Lorig, Ross Township, Allegheny County,
Pa., assignor to United States Steel Company,
a corporation of New Jersey

Application January 13, 1950, Serial No. 138,389

13 Claims. (Cl. 271—2.6)

1

This invention relates to a method of and apparatus for automatically centering and aligning moving objects, especially strip and strip-like materials. In the processing of metal strip, the strip is conveyed over rolls in the uncoiled condition. When the strip is conveyed over a roll to the processing equipment it is likely that the strip will be fed at a slight angle to the roll. Because of this, the strip will work its way across the face of the roll. In addition, the camber and/or lateral curvature which is present in the finished strip due to rolling difficulties causes the strip to approach the roll at an angle, this also causing the strip to move across the face of the roll. In order to keep the strip in the desired path of travel, various expedients have been resorted to. One of the most common is the use of stationary or rotatable side guides against which the edges of the strip bear. In some instances side guides have been used in conjunction with looper pits to force the strip back on the desired center line. The use of abnormally high strip tension has been tried in an attempt to keep the strip aligned. Another method of operation is to periodically slip or slew the strip back into its approximate proper position on the conveying roll. All of the above methods of centering strip tend to abrade and mutilate the strip edges and in some instances cause the edges of the strip to be stretched beyond the elastic limit of the metal. Diagonal or lateral surface scratches are also formed on finely finished flat products of all kinds, these scratches being detrimental to subsequent operations and together with edge damage result in the scrapping of a large percentage of the material being processed. The problems discussed above also exist in belt conveyors and drive belts used in conjunction with belt pulleys. If the belt is made of rubber or other relatively soft material, it is more easily damaged. In addition to the methods of aligning strip mentioned above, crown rolls have been used to center materials having a low modulus of elasticity such as textiles, rubber and composition belts.

One type of apparatus for centering and aligning strip is shown in my copending application Serial No. 97,218, filed June 4, 1949.

It is an object of the present invention to provide apparatus for automatically centering moving objects without damage thereto.

Another object is to provide such apparatus which does not depend upon contact with the edge of the strip or abnormal tensioning of the strip to keep the strip in center alignment.

A further object is to provide a method of

2

keeping the longitudinal axis of a moving strip in a constant vertical plane.

These and other objects will be more apparent after referring to the following description and attached drawings, in which:

Figure 1 is a sectional view of one specific embodiment of my device;

Figure 2 is a sectional view taken on the line II—II of Figure 1;

Figure 3 is a fragmentary view, similar to Figure 1, showing a slight modification of my device;

Figure 4 is a sectional view showing another modification;

Figure 5 is a sectional view showing a further modification;

Figure 6 is a sectional view taken on line VI—VI of Figure 5;

Figure 7 is a view, partly in section, of still another modification;

Figure 8 is a sectional view taken on line VIII—VIII of Figure 7;

Figure 9 is a sectional view of a pair of pinch rolls embodying my invention; and

Figure 10 is an end elevation of the rolls of Figure 9.

Referring more particularly to Figures 1 and 2 of the drawings, the reference numeral 2 indicates a rotatable roll over which a strip or strip-like material S, such as a conveyor belt, passes.

The roll is provided with a plurality of flexible projections 4 and 6 which are inclined radially downward toward the axis of the roll away from the transverse center of the roll. The roll 2 has a shaft 8 on which is mounted a sleeve 10 made of rubber, neoprene, leather, fabric, or other resilient material. The projections 4 and 6 are provided on the sleeve 10 by means of slots 12 which extend circumferentially around the periphery of the roll.

If it is desired to have a smooth surface on the periphery of the roll, the slots 12 may be filled with a material 14, such as sponge rubber, having a much greater elasticity than the projections. The roll may be cylindrical, concave or convex as desired to suit various installations. The projections 4 and 6 preferably are arranged at an angle between 45 and 80° to the axis of the roll. The roll shaft 8 is supported by means of bearings 16 arranged in housing 18. If it is desired to drive the roll, an extension 20 can be provided at one end of the shaft 8. A thrust ring 22 is provided between each end of the sleeve 10 and the adjacent bearing 16. When the strip S passes over the roll surface it bends the projections 4 and 6 inwardly toward the center of the

roll.

roll as shown in Figure 1. As long as the strip is centered on the roll and the bearing pressure of the strip on the roll is uniform over its full width, no lateral movement of the strip will occur when it is conveyed over the roll. If, however, the strip is off-center or the strip contact pressure is non-uniform from side to side, the projections 4 or 6 having the greatest total area in contact with the strip and the greatest total pressure will force the strip toward the center. In other words, as shown in Figure 1, if more of the strip is to the right of the transverse center line of the roll, the projections 6 will have a greater area in contact with the strip and will force the strip to the left until the strip centers itself. In certain applications there will be only line contact between the roll and the objects passing thereover. In other instances, such as shown in Figure 2, the strip S may lead onto the centering roll at point 24 and leave the roll at point 26. The roll may be either a driven or an idler roll and P_2 is greater than P_1 . In this example, the pressure of the strip S against the roll surface will gradually increase between point 24 and point 28 and decrease between points 28 and 26. The shape of the groove in the rolls is immaterial as long as the projections 4 and 6 are inclined as set forth above.

Figure 4 shows a second embodiment of my invention in which the roll is made up of a plurality of resilient discs 30 mounted on a threaded shaft 32. The discs 30 may be made of the same material as sleeve 10 or they may be made from metal if they are sufficiently flexible to bend under pressure. The discs 30 are inclined radially away from the shaft 32 toward the center line of the roll. Spacers 33 are provided between the discs with a center clip or cone 34 being provided on the transverse center of the roll between the two center discs. An end clip 36 on each end of the shaft is held against the end discs 30 by means of a nut 38 which is threaded on the shaft 32, thus holding the discs 30 in assembled position.

Figures 5 and 6 show another embodiment of my invention in which the projections 4 and 6 are knobs 40 arranged in spaced apart relationship both longitudinally and circumferentially of the roll. The knobs 40 are formed in a sleeve 42 mounted on a shaft 44.

Figures 7 and 8 show a further modification in which the projections 4 and 6 are formed by providing holes 46 in the outer periphery of the roll. These holes extend radially downwardly toward the axis of the roll away from the transverse center of the roll.

In each of the embodiments, the space between the projections may be filled with sponge rubber or other highly elastic material in the same manner as shown in Figure 3. Also, if desired, the outer periphery of the rolls may be grooved longitudinally to secure greater resilience on the surface. This is shown at 48 in Figures 7 and 8. In all instances, the functioning of the roll is the same as that described for Figure 1. It will be understood that the term "transverse center line" as used in the claims of the specification is not limited to the exact geometrical center of the roll since the functioning of the roll will be the same regardless of whether there are a greater number of projections 4 or a greater number of projections 6. In each instance, the strip S will be centered at a point between the projections 4 and 6.

In some instances it may be desired to transfer the object being conveyed across the surface of the roll and discharge it from one end thereof.

In this case all the projections will extend radially downwardly toward the axis of the roll away from the direction in which it is desired to move the object.

Figures 9 and 10 show still another embodiment of my invention. In this embodiment the projections 4 and 6 are mounted on a resilient member 50, which is provided with an air pocket 52 therein. The member 50 is mounted on a shaft 54 and, if desired, rigid rims 56 may be provided on the shaft 54 one on each side of the sleeve 50. This construction, which is particularly adapted for pinch rolls, enables the contact distance 58 between the rolls to be increased, thus assisting in holding the strip S in alignment while rotating the rolls.

While several embodiments of my invention have been shown and described, it will be apparent that other adaptations and modifications may be made without departing from the scope of the following claims.

I claim:

1. Apparatus for automatically centering a moving object comprising a rotatable roll over which the object passes, said roll having a plurality of flexible projections on its outer periphery arranged on both sides of a transverse central plane, said projections being undercut and inclined radially toward the axis of the roll away from the said transverse central plane.

2. Apparatus for automatically centering a moving object according to claim 1 in which the projections are formed by means of slots extending circumferentially around the periphery of the roll.

3. Apparatus for automatically centering a moving object according to claim 1 in which the projections are formed by means of a roll shaft, resilient discs mounted in spaced apart relationship on said shaft, said discs being inclined radially away from said shaft toward the said transverse central plane, and means for holding said discs on said shaft.

4. Apparatus for automatically centering a moving object according to claim 1 in which the projections are formed by means of a roll shaft, resilient discs mounted in spaced apart relationship on said shaft, said discs being inclined radially away from said shaft toward the said transverse central plane, spacers on said shaft between the discs, an end clip on each end of the shaft bearing against the end discs, and means for holding said end clips firmly against the end discs.

5. Apparatus for automatically centering a moving object according to claim 1 in which the projections are formed by means of holes extending from the outer periphery of the roll radially toward the axis of the roll away from the said transverse central plane.

6. Apparatus for automatically centering a moving object according to claim 1 in which the roll comprises a shaft, and a resilient member having an air pocket therein mounted on said shaft, said projections being supported on said resilient member.

7. Apparatus for automatically centering a moving object comprising a rotatable roll over which the object passes, said roll having a plurality of flexible projections on its outer periphery arranged on both sides of a transverse central plane, said projections being undercut and inclined radially toward the axis of the roll away from the said transverse central plane, the space between the projections being filled with a mate-

rial having much greater elasticity than the projections.

8. Apparatus for automatically centering a moving object according to claim 7 in which the projections are formed by means of slots extending circumferentially around the periphery of the roll.

9. Apparatus for automatically centering a moving object according to claim 7 in which the projections are formed by means of a roll shaft, resilient discs mounted in spaced apart relationship on said shaft, said discs being inclined radially away from said shaft toward the said transverse central plane, and means for holding said discs on said shaft.

10. Apparatus for automatically centering a moving object according to claim 7 in which the projections are formed by means of a roll shaft, resilient discs mounted in spaced apart relationship on said shaft, said discs being inclined radially away from said shaft toward the said transverse central plane, spacers on said shaft between the discs, an end clip on each end of the shaft bearing against the end discs, and means for holding said end clips firmly against the end discs.

11. Apparatus for automatically centering a moving object according to claim 7 in which the projections are formed by means of holes extending from the outer periphery of the roll radially toward the axis of the roll and away from the said transverse central plane.

12. Apparatus for automatically centering a moving object according to claim 7 in which the roll comprises a shaft, and a resilient member having an air pocket therein mounted on said shaft, said projections being supported on said resilient member.

13. A method of keeping the longitudinal axis of a moving strip in a constant vertical plane which comprises pulling the strip over a roll having a plurality of flexible undercut projections on its outer periphery inclined radially toward the axis of the roll away from the said vertical plane, and applying sufficient tension to the strip to deflect the projections in contact therewith toward the axis of the roll.
